UNITED STATES PATENT OFFICE.

ASA C. STAPLES, OF WEST BRANCH, IOWA.

METALLIC PAD FOR HORSE-COLLARS.

SPECIFICATION forming part of Letters Patent No. 256,172, dated April 11, 1882.

Application filed September 30, 1880. Renewed March 6, 1882. (Model.)

To all whom it may concern:

Be it known that I, ASA C. STAPLES, of West Branch, in the county of Cedar and State of Iowa, have invented certain Improvements in 5 Metallic Pads for Horse-Collars, of which the following is a specification.

My invention relates to a new and improved metallic pad for horse-collars; and it consists in certain details of construction which will be 10 hereinafter defined, and then specifically pointed out in the claims.

Figure 1 is a plan view of a hinge provided with a slide and set-screws for attaching one end of the pad to the collar. Fig. 2 is a plan 15 view of the hinge-hooks to which the opposite end of the pad fastens when the collar is in place on the animal's neck. Fig. 3 is a plan view of the pad. Fig. 4 is a cross section at the line *xx*, Fig. 3.

20 A is the metallic pad, having the hinge-pivots B B' attached thereto. C is the hinge-leaf, riveted or otherwise fastened to the end E of the collar F; and D is a slide to hold the hinge in place on the hinge-pivot B' by means of 25 screws *h h*, and made adjustable by means of the slots *i i*. By this means the pad is easily detached from the collar to admit of a pad of different length being attached to suit any sized animal.

30 The slide D is provided with hooks *kk*, which hooks catch over and hold firmly the hinge-pivots B' of the pad A. The hinge-leaf G, Fig. 2, is attached to the opposite end of the collar, and has the hooks *ll* attached to it, which 35 hooks catch over and hold the hinge-pivots B when the collar is in place on the horse's neck. The ends or shoulders (seen at H H) of the hinge-leaves are made slanting or tapering, as seen in the drawings, to permit the ends *ll* of the 40 hinge-pivots B to draw down tightly into the bottom of the recesses, and thereby prevent all rattle or wear upon the parts in contact. The rib J is cast onto the metallic pad for the purpose of giving strength to a light pad. By 45 this construction it will be readily seen that the upper end of the collar cannot be pressed nearer together than a given distance, governed by the length of the pad used, thereby keeping off all undue pressure from the sides 50 of the animal's neck.

The hinge-pivots B' rest in the recess O,

formed by means of the hinge-leaf C and slide D, and the hinge-pivots B rest in the recess O', formed in the hinge-leaf G. A distinctive feature of this invention is the facility with 55 which it may be placed on the animal's neck and removed, the operation being as follows: The hinge-pivots B' being held in the recess O of the hinge-leaf C, the collar is pressed up onto the animal's neck, when the hinge-pivots B 60 fall readily into the recess O' of the hinge-leaf G, and the operation is complete.

When it is desired to remove the collar a slight pressure upward on the same and a downward pressure on the pad will relieve the 65 hinge-pivots B from the hooks *ll* of the hinge-leaf G, and the collar drops from the animal's neck at once. The hinge-leaves C and G are riveted or otherwise fastened to the upper end 70 of the collar, and their upper edges are sloped 75 to fit against the pad and held by the hinge-pivots. It will be readily seen that it is impossible for the lower edges of the hinge-leaves to be pressed inward, and by this means it effectually prevents all undue side pressure upon the animal's neck.

Having thus fully described my invention, what I claim, and desire to secure by Letters Patent, is—

1. The hinge-leaf C, attached to the collar, 80 in combination with the slide D and hinge-pivots B', attached to the pad, substantially as set forth.

2. In combination with the hinge-pivots B', attached to the pad, the hinge-leaf C and the 85 slide D, provided with the hooks *kk*, substantially as set forth.

3. In combination with the hinge-leaf C and hinge-pivots B', attached to the pad, the slide D, provided with the slots *ii* and hooks *kk*, 90 substantially as set forth.

4. In combination with the pad A, provided with the hinge-pivots B, the hinge-leaf G, provided with the recess O' and hooks *ll*, for the purpose specified.

5. The pad A, provided with the rib J, and the hinge-pivots B B', cast as integral parts of the pad, substantially as set forth.

ASA C. STAPLES.
